ARTICLE HANDLING APPARATUS

Sidney A. Corren, New York, N. Y., assignor to
Nassau Smelting & Refining Company, Incorporated,
New York, N. Y., a corporation of
New York

Application January 13, 1944, Serial No. 518,090

8 Claims. (Cl. 29—283)

1

This invention relates to article handling apparatus, and more particularly to apparatus for separating enclosing parts of articles from parts enclosed thereby.

In order to reclaim metal forming the shells of worn out dry cells, battery elements contained in such shells must be removed therefrom. Previous to this invention, such elements were removed by hand or were pressed from the shells by apparatus requiring a large amount of manual handling of the batteries in its operation which thereby rendered the cost of such reclamation prohibitive.

It is an object of this invention to provide new and improved article handling apparatus.

One device embodying the invention comprises a reciprocal pneumatically actuated plunger, a rotatable carrier positioned beneath the plunger, which carrier is provided with a plurality of compartments for holding dry cells to be operated upon, a wall adjacent to a portion of the circumference of the carrier, a plurality of fins extending from the wall towards the carrier and so positioned that one end of each of the fins is nearer the carrier than is the other end, whereby the dry cells are firmly held in position in the compartments, means for intermittently rotating the carrier so as to position the dry cells beneath the plunger, and a finger so positioned as to disengage the stripped shells from the compartments.

A complete understanding of the invention may be obtained from the following detailed description of one embodiment thereof, when read in connection with the appended drawings, in which

Fig. 1 is a fragmentary, top plan view of an apparatus embodying the invention;

Fig. 2 is a vertical, partially sectional view thereof taken on line 2—2 of Fig. 1;

Fig. 3 is a horizontal sectional view taken on line 3—3 of Fig. 2;

Fig. 4 is an enlarged, fragmentary sectional view taken on line 4—4 of Fig. 1;

Fig. 5 is an enlarged perspective view of a portion of the apparatus, and

Fig. 6 is an enlarged, fragmentary perspective view of a portion of the apparatus.

Referring to the drawings, a cylindrical article carrier 10 having a plurality of U-shaped pockets 11—11 formed therein at equidistant points about the periphery thereof is rotatably mounted upon a post 12 (Fig. 2) extending through apertures in a base plate 13 and a base 14 forming part of a support 15 and secured in position by means of a nut 16. The post 12 has an L-shaped passage

17 formed therein for lubricating purposes, and a nut 18 having a hexagonal flange 20 formed thereon is threaded upon its upper end to secure the carrier 10 rotatably upon the post 12. The carrier 10 is provided with an annular groove 24 formed around the periphery thereof to a depth equal to that of the pockets 11—11 and a plurality of horizontal arcuate fins 23—23 formed on the interior surfaces of the pockets 11—11 which project into the pockets.

Each of a plurality of blocks 25—25 is secured upon the upper surface of the carrier 10 adjacent to the outer periphery thereof and approximately midway between each adjacent pair of the U-shaped pockets 11—11. The blocks 25—25 have inwardly and downwardly bevelled ends 26—26 which are predisposed so that in going around the carrier in a counterclockwise direction, as seen in Fig. 1, the bevelled ends 26—26 will be encountered first as each block is reached.

A yoke 27 (Figs. 1, 2 and 6) resting upon the carrier 10 has a circular aperture 28 formed therein which surrounds the lower periphery of the nut 18. The yoke 27 also has formed therein a notch 30 and aligned bores 31—31, which extend outwardly from the notch 30. One end of a handle 32 is pivotally mounted upon a pin 37 passing through the bores 31—31 and a bore 36 formed in the handle 32. The handle 32 has a bevelled surface 35 formed thereon, which is complementary to the bevelled ends 26—26 on the blocks 25—25. When the handle 32 is held against the carrier 10 and rotated in a counterclockwise direction, as viewed in Fig. 1, the bevelled surface 35 is brought against one of the bevelled ends 26—26 of the block 25—25 and causes the carrier to rotate around the post 12.

A generally triangular plate 38 (Figs. 1 and 2) having an aperture 40 and bores 41—41 formed therein is secured by the nut 18 and bolts 43—43 upon the yoke 27 and upon arcuate blocks 44 and 45 having bores 46—46 therein. The bolts 43—43 project through the bores 41—41 and 46—46 and are threaded into apertures 47—47 formed in the base plate 13. An arcuate cam 48, having ribs 50—50 projecting from the inner periphery thereof and the ends 51 and 52 thereof beveled, is secured to the blocks 44 and 45 by screws 55—55. The block 45 is positioned closer to the carrier 10 than is the block 44 so that the portion of the cam 48 secured to the block 45 is closer to the outer periphery of the carrier 10 than is that portion of the cam which is secured to the block 44.

A stripper 56 (Fig. 3 and 5) having a finger

51 formed thereon is secured on the plate 13 by a bracket 58. The finger 51 has an arcuate surface 60 formed on the end thereof and projects into the groove 24 formed in the carriage 10 with the surface 60 resting on the inner surface 6 of the groove.

A pneumatic cylinder 62 (Fig. 2) supported by a standard 63 forming a part of the support 15 has conduits 65-65 leading from an air valve (not shown) of a conventional type which is connected to a supply of compressed air. The base plate 13, the base 14 and the plate 38 have aligned openings 67, 68 and 69, respectively, which are directly below a plunger 70 which may be actuated by the pneumatic cylinder 62. The openings 67, 68 and 69 are concentric with the circular portions of the U-shaped pockets 11-11 when the pockets are positioned in alignment therewith.

In the operation of the apparatus described hereinabove, one of a plurality of dry cells 71-71, for example, a flashlight cell, having its outer paper covering removed, is placed in one of the pockets 11-11 at the loading position, which has been designated A in the drawings. The handle 32 is moved into engagement with one of the blocks 25-25 and is rotated to rotate the carrier 10 in a counterclockwise direction, as viewed in Fig. 1, through an angle of about 60°. When the handle 32 is moved into engagement with any of the blocks 25-25, the surface 35 is pressed against the bevelled end 26 of the block and the handle 32 is thereby forced against the carrier 10. During the above described rotation the dry cell 71 rides over the plate 13 and is carried to the position designated B where it is forced by the bevelled end 51 and the ribs 50-50 of the cam 48 into contact with the fins 23-23 in the pocket 11 in which it is positioned.

A second dry cell then is placed in the next succeeding pocket 11 (Fig. 1) reaching the loading position A. The handle 32 is disengaged from the block 25 which it is engaging, is lifted to clear the block and is then rotated clockwise, as viewed in Fig. 1, until it is in a position to engage another one of the blocks 25-25. The handle 32 is then lowered into engagement with the latter block and is again rotated to turn the carrier 10 until the first-mentioned cell of the dry cells 71-71 is carried to the ejection station C directly beneath the plunger 70 and is in alignment with the openings 67, 68 and 69 formed in the base plate 13, the base 14 and the plate 38, respectively. As this dry cell is moved from position B to the ejection station C, the ribs 50-50 of the cam 48, which are positioned closer to the carrier 10 at the end 52 of the cam than at the end 51 thereof, will bear against the shell 72 of the dry cell and force the dry cell tightly against the fins 23-23 so that the fins 23-23 and ribs 50-50 will grip the cell sufficiently to somewhat corrugate the shell thereof and thus securely hold the cell below the plunger 70.

The compressed air valve (not shown) is then operated manually to cause the plunger 70 (Fig. 2) to be forced downward to eject the interior elements of the dry cell from the shell 72 thereof of which is held against movement by the fins 23-23 and ribs 50-50. The stroke of the plunger 70 is sufficiently long to permit it to remove the entire center portion of the cells from the surrounding shells. After the downward motion of the plunger 70 has ceased, the valve is shifted to retract the plunger. The fins 23-23 and ribs 75

50-50 securely hold the shell 72 throughout the ejecting and retracting operations.

A third one of the dry cells 71-71 (Fig. 1) then is placed in the next pocket 11 and the carrier 10 is rotated until the second mentioned dry cell is directly under the plunger 70 and the ejecting operation is repeated. As the carrier 10 is rotated, the empty shell 72 of the first mentioned dry cell is moved from the ejecting station C and is retained in the carrier 10 until it engages the finger 51 projecting into the groove 24 at the station D, which finger removes the shell from the carrier. As the carrier 10 is rotated between the ejecting operations, the succeeding empty shells 72-72 are withdrawn from their respective pockets 11-11 by the finger 51 and are guided by the stripper 56 off the plate 13 into any suitable receptacle (not shown) from which they may be removed as desired for further reclaiming operations.

Large numbers of dry cells may be handled by the use of the above described apparatus within a comparatively short period of time, thus reducing the labor and expense normally required to prepare the shells thereof for reclaiming operations. The above described embodiment of the invention may be modified without departing from the spirit and scope of the invention. For example, the handle 32 may be removed and a suitable intermittent drive may be attached to the carriage 10 to rotate it automatically. Also, cams may be spacedly positioned on the carriage and the operating mechanism of the air valve may be positioned in the path of the cams to automatically actuate the plunger whenever one of the dry cells is positioned beneath it.

What is claimed is:

1. In an article handling apparatus, a carrier provided with a U-shaped recess formed in one edge thereof, and also provided with a groove extending along that edge, said carrier having fins thereon projecting into said recess, means for moving the carrier to move the recess along a predetermined path, a cam having ribs formed thereon extending along a portion of said edge with one end thereof closer to said edge than its other end for wedging an article carried in the recess between the ribs and the fins as the article is moved to a point opposite the cam, and a finger extending into the groove for engaging and withdrawing the article from the recess as it is moved beyond the cam.

2. In an article handling apparatus, which comprises a carrier having a U-shaped recess formed in one edge thereof for receiving an article, said carrier also being provided with a groove formed therein along said edge to a depth equal to the depth of the recess, means for moving the carrier to carry an article in the recess, an elongated cam rigidly positioned adjacent to the path of the recess with one end thereof closer to the recess than the other end thereof for wedging the article between the walls of the recess and the cam, and means projecting into the groove for withdrawing the article from the recess.

3. In an article handling apparatus, a mechanism for securing a dry cell, which comprises a base plate having an opening formed therein, a disc having a plurality of U-shaped article-carrying recesses formed in the periphery thereof rotatably mounted on the base plate, said disc also being provided with a groove in the periphery thereof of a depth equal to that of the recesses and intersecting the recesses, a plurality of arcuate fins projecting into the recesses, means for

rotating the disc, an arcuate cam having ribs formed on the inner periphery thereof secured to the plate with one end thereof secured nearer to the periphery of the disc than the other end, whereby as one of the cells is moved the fins in the recess and the ribs of the cam securely keep the outer shell of the cell therebetween, and an extracting member having a finger formed thereon which lies against the inner periphery of the groove for forcing the emptied shell from the recess as the disc is further rotated.

4. In an article handling apparatus, a carrier movable over a predetermined path, said carrier having a U-shaped recess formed on one edge thereof and also provided with fins projecting into the recess for engaging an article to be held therein, means for moving the carrier over the predetermined path, and a wedge positioned adjacent to the path for forcing an article in the recesses against the projecting fins, said wedge being provided with ribs extending along the predetermined path for engaging and keeping an article in the recess.

5. In an article handling apparatus, a carrier having a recess formed in one edge thereof and also being provided with a plurality of fins projecting into the recess for engagement with an article to be held therein, a cam having a plurality of ribs extending therealong positioned adjacent to said edge of the carrier, said ribs being closer to said edge at one end of the ribs than at the other end thereof, means for moving the carrier to move said edge along the predetermined path, whereby an article positioned in the recess is wedged securely between the fins and the ribs.

6. In an article handling apparatus, a carrier provided with U-shaped recesses formed in one edge thereof and also provided with fins projecting into the recesses, a cam having ribs formed thereon extending along a portion of said edge of the carrier with one end thereof closer to said edge than its other end, and means for moving the carrier to move the recesses along a predetermined path adjacent to the cam, said carrier being moved in a direction in which the recesses move from the more remotely positioned end of the cam to the closer end of the cam, whereby an article positioned in one of the recesses is securely gripped between the ribs and the fins as the article is moved to a point adjacent to the end of the cam which is closer to said edge of the carrier.

7. An article gripping apparatus including a carrier, a base, means mounting the carrier on said base for movement along a fixed path, an article recess in a side edge of said carrier opening at its side transversely of said path and

open at each end, an elongated cam fixed to said base extending along said path at the open side of said recess, said cam being provided with a plurality of immovable elongated ribs each extending along said path and being positioned progressively closer to said recess along their length to gradually reduce the space between said ribs and said recess as said recess moves along said path, and means for moving said carrier along said path whereby the ribs are gradually forced into the sides of an article to recess and tightly grip the same.

8. An article gripping apparatus, a base, a carrier mounted on said base for movement along a fixed path, an article recess in said carrier opening toward said path and completely passing through said carrier, a plurality of fins positioned along the face of the wall of the recess, an elongated cam positioned lengthwise of said path having a plurality of ribs running along the length thereof and facing said recess, said cam secured to the base and positioned progressively closer to said carrier along the path, and means for moving said carrier along said path whereby the fins and ribs are gradually forced into the side of an article to recess and tightly grip the same.
